UNITED STATES PATENT OFFICE.

MAX JAEGER, OF LONG ISLAND CITY, NEW YORK, ASSIGNOR TO ANCHOR CAP & CLOSURE CORPORATION, OF NEW YORK, N. Y., A CORPORATION OF NEW YORK.

PACKAGE-TRANSFERRING MACHINE.

Application filed May 26, 1920. Serial No. 384,305.

To all whom it may concern:

Be it known that I, MAX JAEGER, a citizen of the United States, residing at Long Island City, in the borough of Queens, State of New York, have invented certain new and useful Improvements in Package-Transferring Machines, of which the following is a specification.

This invention pertains generally to the packing or packaging art, and has to do specifically with certain improvements in mechanism to be employed in the packing and sealing of containers such as are commonly utilized for packaging foodstuff and the like.

15 It resides in the provision of a new and advantageous mechanism designed for association in common with a machine for filling vessels and a machine for sealing them, in such fashion that such machines are brought 20 into coordinated cooperation, and may be so operated continuously and without the necessity for intelligent control.

The general object of the invention is to provide an improved mechanism for automatically handling and transferring filled vessels or containers, such as tumblers, jars, cans and the like, from a filling machine to sealing position in a sealing machine, and moving them from the sealing position to a 30 suitable removing device, upon the sealing operation having been effected.

One of the objects which the present invention is to accomplish is the provision of an automatically operating machine which 35 is adapted to receive filled vessels from filling machines of types now commonly in use, and deliver them to sealing machines of types also now commonly in use, effecting a change in the rate or period of delivery of 40 the vessels such as may be necessary to compensate for the difference in rate of operation between the filling and the sealing machines.

A further object of the invention is the 45 provision of such a mechanism which is designed to accomplish a gradual acceleration in the rate of travel of the filled vessel from the time it leaves the filling machine, such as to properly position it relative to preceding 50 vessels, with respect to the periodicity of the sealing machine, and to produce such acceleration without subjecting the vessels to such handling as will spill or splash out their liquid contents.

55 A further object of the invention is the

provision of such a mechanism which will operate continuously and automatically to receive filled vessels from a filling machine at certain intervals and move them successively and continuously to sealing position 60 in a sealing machine at increased definite and regular intervals.

A further object of the invention is the provision of a mechanism having the characteristics above specified, which is adapted 65 for cooperation with a machine for assembling caps or closures on the vessels in the course of their transfer from the filling machine to the sealing machine.

Further objects of the invention contemplate the provision of a machine having the characteristics above specified, which is of such strong and simple construction and such accurate and precise operation as to insure its proper performance under all conditions commonly encountered in the industry, 70 to insure its longevity, to facilitate its being kept clean and in repair, and to obviate the necessity for specially trained or skilled operators.

Other and further objects of the invention will be obvious upon an understanding of the illustrative embodiment about to be described, or will be obvious from the accompanying drawings, or indicated in the appended claims; and various advantages secured by the invention, other than those hereinafter specifically referred to, will occur to one skilled in the art or become evident upon the employment of the invention 85 in practice.

In the drawings Figure 1 illustrates a top or plan view of an embodiment of the invention, showing it in association with certain elements of a filling machine, a cap assembling machine, and a sealing machine;

Figure 2 is a top or plan view of a portion of the mechanism illustrated at the right-hand end of Figure 1;

Figure 3 is an elevational view of the 100 same portion shown in section along line 3—3 of Fig. 2;

Figure 4 is a detail in the nature of a section on the line 4—4 of Figure 2;

Figure 5 is a plan or top view of a portion 105 of the mechanism shown at the left-hand end of Figure 1; and

Figure 6 is a front sectional elevation of the same portion of the mechanism, but with certain parts in altered positions.

Described generally, the invention comprises an arrangement of a turn table or distributing device containing pockets adapted to cooperate with a filling machine to receive vessels therefrom at the intervals determined by the operation of said filling machine, together with a conveyor associated with said turn table and cooperating therewith to produce an acceleration in the rate of movement of the vessels over their rate of movement in the filling machine, so that the interval between them is increased; and an interval determining device cooperating with the said accelerating mechanism in such fashion as to establish the transmission of the vessels at definite intervals, and a handling mechanism associated with the interval determining means and with a sealing device whereby the vessels are moved successively from the control of the former into the control of the latter, and from the latter to a suitable removing mechanism; the movement of each container throughout being continuous and substantially in a straight line.

The specific description of the illustrative embodiment will be understood by reference to the identifying characters applied to the accompanying drawings, in which the letter C designates generally a filling machine of well known type, the letter S designates generally the package transfer mechanism, and the letter B designates generally certain elements of a sealing machine of a well known kind. It will be understood that the container conveying portion of the filling machine is in the form of an endless belt or platform on which are supported guiding seats or pockets C' adapted for the reception and retention of vessels or containers while they are being conveyed to the filling nozzles, being filled thereby, and being conveyed away therefrom, the direction of movement of the turn table 5 being in counter clockwise direction. The sealing machine includes a platform B' and cooperating mechanism operating intermittently to secure a closure or a cap upon a vessel positioned on the platform. The transferring mechanism includes a table 1 which extends into association with the platform B' and with the conveyor of the filling machine. This table has marginal guides 2 adjustable toward and from its median line for the accommodation of vessels of different diameters by means of adjustable arms on which the guides are mounted. A housing 4 forms a support for the table 1 and for associated mechanism, including a distributing device in the nature of the turn table 5, mounted in the housing to rotate on a vertical axis above the table 1, at the end designed for association with the conveyor of the filling machine. This turn table is driven through a train of gearing 6 actuated from a sprocket

7 mounted in the housing 4 on a horizontal axis. The turn table 5 is formed with peripheral pockets 8 disposed at definite intervals and adapted for the reception of vessels or containers projected into its orbit from the seats of the filling machine, and the turn table is adjustably mounted on its hub 5^a by means of manipulative members 5^b operating through slots 5^c, so that the pockets 8 may engage properly the vessels on seats C'. Supported in the housing 4 on horizontal axes are pairs of flanged sheaves or pulleys 9 carrying belts 10 which they transmit longitudinally of the table 1, and which belts comprise an accelerating device as is hereinafter explained. The positions of the pulleys 9 are such as to bring the upper surfaces of the belts 10, in their upper stage, substantially flush with the upper surface of the table 1, and adjusting means whereby they may be so positioned is provided in the guide plates 11. (See Figure 4.) These guide plates constitute, in effect, depressed portions of the table mounted on trunnions 11^a which are carried eccentrically on rotatable spindles 14. By this arrangement the elevation of the plates 11 may be varied so that the upper surface of the belts 10 may be disposed at the desired level relative to the upper surface of the table 1. Between the belts the plates carry upstanding longitudinal marginal guide members 15 of substantially the thickness of the belts, said guide members 15 being spaced apart to provide a narrow slot which is aligned with a slot 1^a extending longitudinally of the table 1. This slot is for the accommodation of the flights or lugs 16 carried by a spacing conveyor chain 17 which is transmitted on the sprocket wheels 7 and 18 operating on horizontal axes in the housing 4, and comprises spacing means for the packages. The sprocket 18 is carried on a shaft 19 which is rotated through a beveled gear 20 by a shaft 21 mounted vertically in the frame of the sealing machine B, and such actuation of the sprocket 18 serves to drive the sprocket 7 and, through the gear train 22, 23 and 24, to rotate the right-hand pulleys 9 and transmit the belts 10 as above described. The disposal of the belts 10 is such that they move below a portion of the orbit of the pockets 8, so that the pockets and the belts progress in the same direction at the point where the pockets first move to position over the belts, and the table 1 and marginal guides 2 are deflected to conform to the orbit of the turn table. At the point of deflection of the marginal guide, an adjustable portion 2^a is inserted, its position being controlled by suitable means 25. The extremity 2^c of the marginal guide is adapted to engage vessels transmitted on the seats C', and deflect them there-out-of and into the orbit of the pockets 8. It will be ob-

served that the rearward walls of the pockets 8 are abrupt and conform to the general contour of the vessels, so that they transmit definite motion to the vessels upon rotation 5 of the turn-table, but that the forward margins of said pockets are involuted so that the vessels may ride along them and out of the pockets.

Inasmuch as the operation of filling the 10 vessels goes on continuously while they are transmitted through a certain zone in the filling machine, they may be transmitted at much closer intervals than are feasible in presenting them to the sealing machine, 15 wherein each vessel must be handled individually, the air exhausted from it, the closure sealed on it hermetically, and the vessel removed from the sealing platform before another can be positioned. Inasmuch as a 20 stopping or slackening of the progressive movement of the vessel after it has been filled increases the danger of its liquid contents being spilled or splashed out, it is highly desirable that the movement of the vessel be 25 continuous and in a substantially straight line and without material or sudden impulses or changes in speed. However, the fact that the sealing machine may require, for illustration, an interval of 12 inches between 30 vessels, while the filling machine requires an interval of but 4 inches, it is obvious that the progress of each vessel must be accelerated materially between the time it leaves the filling machine and the time it reaches 35 the sealing platform. The interval at which the successive vessels are delivered to the sealing machine is established in the first instance by the chain 17. It being timed substantially accurately with respect to the sealing 40 machine, and its linear speed being considerably higher than the peripheral speed of the turn table 5, which is properly timed with respect to the filling machine, it results that the speed of the vessels 45 must be accelerated between the two. The acceleration in the movement of the vessels is accomplished through the cooperation of the belts 10 with the turn table 5 and with the chain 17. It occurs in this 50 fashion: The belts 10 are transmitted at the same speed as the chain 17, which is materially faster than the movement of the turn table 5. As the vessels are moved successively into cooperation with the deflecting 55 guide 2^c by the movement of the conveyor of the filling machine, their movement will be accelerated because of the fact that they are transmitted away from the center on which the conveyor turns at that point. This ac- 60 celeration obviously will be gradual so that, when the vessel comes into the orbit of one of the pockets 8, then moving on a longer radius and consequently at a greater peripheral speed than the conveyor of the filling 65 machine, it will be picked up at this accele-

rated speed and transmitted at an increased speed to a point where it moves onto the portions of the belts 10 projecting below the orbit of the pockets. The movement of the vessel onto the belts will, of course, be 70 gradual, the tendency of the belts to increase its speed becoming more effective as the area of contact between the bottom of the vessel and the belts increases. This accelerating influence of the belts is effective in the same 75 direction as the movement of the turn table, and tends to cause the vessel to ride ahead of the back wall of the pocket along the involute forward wall thereof until, at a time determined by the adjustment of the member 2^a, the vessel is freed of the restraint of the cooperating pocket and marginal guide, and is carried forward out of the pocket by the movement of the belts. By properly 80 timing the turn table 5 and the belts 10 with the chain 17 through the gearings 6 and 22, each vessel will be deposited on the belts in 85 advance of a flight 16, and when the vessel is transported by the belts to the point where the latter pass from the surface level of the 90 table to go around the pulley 9, there will be a slight gradual negative acceleration of the movement of the vessel as it becomes subjected to the friction of the stationary 95 table surface. This slight negative acceleration, which does not materially or suddenly retard the vessel, permits the adjacently following flight 16 to catch up with it and engage it while it is still moving forward, and assume control of it for the continuation of the transfer operation. At a point designated by the dotted diagram 26, a 100 cap assembling mechanism may be rendered effective upon the vessel to place a cap or closure upon it preparatory to the operation of the sealing machine thereon. This affords a certain amount of safeguard against spilling of the contents during the succeeding handling of the vessel. This cap-placing 105 operation having been effected without changing the acceleration of the vessel, it is moved continuously forward in a straight line and uniform speed to the point at which it is removed from the control of the spacing chain to be positioned on the platform B. 110

As a means for accomplishing this transposition of the successive packages, a rotary turret 30 which comprises positioning means (see Figures 5 and 6) is mounted for operation adjacent the sprocket 18, being removably affixed to a hub 31 which is keyed to the upper end of a shaft 32 mounted in bearings 34 of a housing 35 which forms a continuation of the housing 4. The attachment of the 115 turret to the hub is by manipulative means 36 whereby the rotary position of the two may be varied. Shaft 32 carries a helical gear 37 through which said shaft and turret 30 are rotated from gear 38 carried on a horizontally extending jack shaft 39. The 120 125 130

latter is rotated through its gear 40 and gear 41 on shaft 19, the speed of rotation of the turret being thus timed with respect to the speed of operation of chain 17 and, through shaft 21, with that of the sealing machine. The turret 30 carries a plurality of upstanding bosses 42 circumferentially distributed adjacent its periphery. On alternate bosses are mounted positioning flights 44 and re-moving flights 45. The latter are secured in fixed position on their bosses by bolts 46, whereas the former are rotatable on their bosses so that they may swing to a position in which they extend radially from the turret or swing back to a substantially tangent position. This may be done conveniently by mounting them on spindles 47 rotatably mounted in the bosses, said spindles carrying at their lower extremities controller arms 48 in which are mounted rollers 49. Traction springs 50 tend to urge the flights 44 to their tangential position, and their position is controlled by said springs and by a cam 51 rotatably mounted on the sleeve 52 on shaft 32. Upon rotation of the turret the edge of the cam is adapted to engage the rollers 49 and swing the arms 44 to their radial position, maintaining them in that position through a certain extent of the rotation of the turret. The position of the active portion of the cam may be varied through adjustment thereof rotatably on the sleeve 52, such adjustment being accomplished through the instrumentality of the arm 54 which extends forwardly adjacent a front opening in the housing 35, and is adjustably secured to a bracket 56 by means of a clamping screw 57. The disposal of the turret and the extent of the flights 44 and 45 are such that the latter include in their orbit, when radially extended, portions of the table over the sprocket 18, the platform B', and the terminus of the conveyor 58, which is disposed on the side of the platform B' opposite the sprocket 18. This conveyor is driven from shaft 39 through gears 59 and 60. The direction of rotation of the turret 30 is such that the flights are moved first across the sprocket 18, then across the platform B' and finally across the conveyor 58. The articulation of the turret with the chain 17 is such that the successive positioning flights 44 cross the sprocket 18 substantially in register with the successive spacing flights 16 of the chain. As a result, a vessel conveyed into the zone of operation of a flight 44 by chain 17 will be picked up by the flight at the same speed that it is transmitted by the chain, and moved to a position on the platform B'. As governed by the position of the cam 51, when the vessel has reached the intended position, the flight which has propelled it thus far will be released from the control of the cam and quickly retracted by its spring 50, leaving the vessel in position

on the platform. The sealing machine being rendered effective at this point in the cycle of the mechanism, the vessel is sealed and ready for removal by the succeeding removing flight 45. This engages the vessel, now sealed, and moves it onto the conveyor 58 by which the vessel is carried forward to any intended point of disposal, such as a washer, labeling machine, or the like. During the time that the vessel is on the platform B' the succeeding vessel is being continuously advanced by the chain, engaged by the next positioning flight 44, and is placed on the platform thereby, after the removal of the preceding sealed vessel, in the manner as just described. The adjustment of the cam 51 permits the operation of the device being accommodated to vessels of different diameters, so that the centering of the vessels on the platform B' relative to the sealing dies, is always assured.

It will be observed, therefore, that this invention provides a machine which is operable continuously and automatically to transport filled vessels through a plurality of operations, changing their spacing and rate of travel to accommodate the periodicity of different machines, without subjecting them to sudden changes in acceleration or position such as would tend to splash out their contents; that the mechanism so provided is adapted to handle vessels accurately and safely at high rate of speed, and without requiring oversight or special training for its operation.

Having thus described my invention, what I claim is:

1. In a machine of the class described, the combination of an accelerating device effective upon successive packages to move them progressively at accelerating speed, spacing means cooperating with the accelerating device for placing the packages at definite space intervals and effective to move them in a substantially straight line at a constant speed, and positioning mechanism operable to take successive packages from the spacing means while in motion and move them severally at a constant speed to a definite position of rest.

2. In a machine of the class described, the combination of an accelerating device effective upon successive packages to move them progressively at accelerating speed, spacing means cooperating with the accelerating device for placing the packages at definite space intervals and effective to move them in a substantially straight line at a constant speed, positioning mechanism operable to take successive packages from the spacing means while in motion and move them severally at a constant speed to a definite position of rest, and means for operating said elements continuously on a series of packages.

3. In a machine of the class described, the combination of a package distributing device operable to move packages substantially along the arc of a circle and to distribute packages successively, a package conveying device cooperating therewith to move packages in a substantially straight line in succession and accelerate their rate of travel to increase their interval, spacing means co-
operating with the conveying device for spacing the moving packages at definite intervals, and positioning mechanism operable to take successive packages from the spacing means and move them at a constant speed to a definite position of rest; said distributing device, conveying device, spacing means and positioning mechanism being effective seriatim upon a package while it is in motion. 70
4. In a machine of the class described, the combination of a distributing device effective to move packages at definite intervals, a positioning device operable upon successive packages at greater intervals, and accelerating and spacing mechanism operating along a substantially straight path between the distributing and positioning devices for accelerating the rate of travel of packages delivered by the former and positioning them at increased definite intervals. 80
5. In a machine of the class described, the combination of a distributing device and an accelerating device arranged for cooperation to move packages progressively, said accelerating device being arranged to frictionally engage packages with a gradually increasing surface contact and operating at a higher progressive speed than the distributing device. 90
6. In a machine of the class described, the combination of a distributing device and an accelerating device movable on different axes and arranged for cooperation to move packages progressively, said accelerating device being arranged to frictionally engage packages with an increasing surface contact to gradually increase their speed and operating at a higher progressive speed than the distributing device. 100
7. In a machine of the class described, in combination, a package distributing device effective to move packages at definite intervals, and a package accelerating device comprising a belt cooperating therewith and effective to move packages relative thereto to increase their rate of travel, said accelerating device being constructed to permit slip between a package and its portions effective thereon. 110
8. In a machine of the class described, in combination, a package distributing device comprising a pocketed turn table effective to engage packages at definite intervals, and a package accelerating device comprising a carrying belt cooperating therewith and effective to move packages relative thereto to increase their rate of travel, the distributing device being operable to move packages to the operation of the accelerating device which is constructed to permit slip between a package and its portions effective thereon. 120
9. In a machine of the class described, the combination of means for continuously advancing packages at definite intervals, spacing means cooperating with said advancing means, a constantly rotating turret associated therewith, flights carried by the turret, and timed to cooperate with the spacing means to engage and move packages presented by the latter, and means for operating the flights at definite intervals to move them out of cooperation with packages. 130
10. In a machine of the class described, the combination of a table arranged to permit the movement of packages thereon in a series, means effective to advance packages continuously thereon at definite intervals, and to space said packages, a rotating turret associated with the table, flights carried by the turret and movable above the table into association with the spacing means to engage and move packages presented thereby, and means below the table for operating the flights at definite intervals to render them ineffective upon packages. 95
11. In a machine of the class described, the combination of a table arranged to permit the progressive movement of packages thereon in a series, of a rotary distributing device, an accelerating device, a positioning device, and a spacing means adapted to move said packages from said accelerating device to said positioning device along a substantially straight path, said distributing device and said accelerating device co-operating to advance said packages and accelerate their speed. 105
12. In a machine of the class described, the combination of a turn-table having spacing members arranged to engage packages for moving them, a belt arranged to have frictional engagement with packages moved by the turn-table, means operating said belt at a higher progressive speed than the turn-table, and means to gradually increase the frictional engagement between a package and said belt when a package is being transferred from said turn table to said belt. 115
13. In a machine of the class described, the combination of a package distributing device having pockets arranged at definite intervals for the reception of individual packages, means for operating said distributing device, an accelerating device co-operating with the distributing device and effective to frictionally engage and remove packages from the pockets and gradually increase their speed, means cooperating with the distributing device to control relative 125

movement of packages by the accelerating device, and means for removing successive packages from the accelerating device.

14. In a machine of the class described, 5 the combination of a turn-table having spaced members arranged to engage packages for moving them, a belt arranged to have frictional engagement with packages moved by the turn-table, means operating 10 said belt at a higher progressive speed than the turn-table, and an adjustable device cooperating with the belt and turn-table to determine the extent of their effectiveness upon packages.

15. In a machine of the class described, 15 the combination of a conveyor having pockets effective to advance packages at definite intervals, a second conveyor cooperating therewith to withdraw packages 20 from the pockets, said second conveyor operating at a greater conveying speed than the first mentioned conveyor to effect a gradual acceleration in the rate of travel of a package engaged thereby, and a spacing device cooperating with the second conveyor to position packages moving at the accelerated rate at definite intervals greater than the intervals of the said pockets.

16. In a machine of the class described, 25 20 in combination a rotary distributing de-

vice, a rotary positioning device adapted to move packages along an arc of a circle, and a moving and accelerating device adapted to engage said packages and move them substantially tangentially to their path 35 on the rotary distributing device along a substantially straight path to the positioning device.

17. In a machine of the class described, 40 a package distributing device adapted to move said packages along the arc of a circle, a rotary positioning device and accelerating and moving devices adapted to engage packages and move them from the rotary distributing device substantially 45 tangentially to their path and deliver them to the positioning device substantially along a tangent to the path of the packages thereon.

18. In a machine of the class described, 50 a mechanism adapted to move packages at a definite space interval, a distributing device to receive said packages from said mechanism and to increase said space interval, an accelerating device adapted to engage said packages while on said distributing device and adapted to increase the speed of said packages and to further increase the space interval therebetween.

MAX JAEGER.
